UNITED STATES PATENT OFFICE.

LEOPOLD OXHANDLER, OF CHICAGO, ILLINOIS.

SHIPPING CONTAINER FOR EGGS AND OTHER FRAGILE ARTICLES.

Application filed June 11, 1921. Serial No. 476,778.

To all whom it may concern:

Be it known that I, LEOPOLD OXHANDLER, a citizen of Russia, who has formally declared his intention of becoming a citizen 5 of the United States, residing at Chicago, county of Cook, State of Illinois, have invented a certain new and useful Improvement in Shipping Containers for Eggs and Other Fragile Articles, and declare the following to be a full, clear, and exact description of the same, such as will enable others skilled in the art to which it pertains to make and use the same, reference being had to the accompanying drawings, which form 10 a part of this specification.

My invention has for its object to produce a simple means in which eggs or other fragile articles may be packed with a minimum amount of labor, without requiring any skill on the part of the packer and which, after the packing has been completed, will permit the eggs or other articles to be shipped long distances or be subjected to rough handling in other ways 25 without danger of breakage.

A further object of my invention is to produce a strong, light, durable shipping crate for eggs or other fragile articles, the crate being adapted to be used over and over 30 again.

The various features of novelty whereby my invention is characterized will herein-after be pointed out with particularity in the claims; but, for a full understanding of 35 my invention and of its objects and advantages, reference may be had to the following detailed description taken in connection with the accompanying drawing, wherein:

40 Figure 1 is a plan view of one of the cell-containing slabs forming part of my invention;

Fig. 2 is a plan view of one of the flats adapted to be placed upon the slabs to form 45 closures for the tops and bottoms of the cells;

Fig. 3 is a vertical section through a case of eggs packed in accordance with my invention; and

50 Fig. 4 is a section taken through a completed package so designed that no enclosing case or box is required.

My improved device consists of two parts, namely a series of slabs and a series of flats, the slabs 1, each having a thickness

at least equal to the length of the eggs to be packed, and filled with cylindrical holes, 2, extending entirely through the same as close together as the mechanical demands of the structure will permit, these holes being at least as large in diameter as the smaller diameter of the eggs to be packed. These slabs are preferably molded out of wood pulp or other fairly light, strong material having cushioning characteristics. 60 The slabs are preferably square, the holes therein being regularly arranged, preferably in parallel rows at right angles to each other, so that the holes in any two slabs will register with each other when the slabs 65 are laid upon each other with their edges coinciding.

The flats, 3, may be made of any usual or suitable material, each preferably having at a plurality of points symmetrically-disposed with respect to the center of the flat, shallow projecting annular flanges, 4, whose outer diameter is the same as the diameter of the holes in the slabs. The flats which are to form the top and the bottom 70 of a package are provided with flanges on one side only while the intermediate flats are flanged on both sides.

In forming a package, one of the slabs 75 is set upon a flat and the holes or cells therein are then filled with eggs. A second flat is then laid on top of the filled slab and a second slab is placed on top of the flat. It will be seen that the upwardly- and downwardly-projecting flanges on the flat interposed between the two slabs interlocks the slabs together so that they will not shift or slide one upon the other. The second layer 80 of eggs is then inserted, and the process of adding flats and slabs and filling the cells 85 in the slabs, is repeated until a stack of the required size is obtained. In the arrangement shown, each slab is designed to contain three dozen eggs and, by piling five of these slabs upon each other, fifteen dozen 90 eggs or what is known as half a crate, may be obtained. Where an enclosing box or container, such as indicated at 5 in Fig. 3, is employed, the assembling of the flats, 95 slabs and eggs, is effected in the box or container.

The package may be made up without the use of an enclosing box or container, if the constituent parts are tied together securely. To this end, the slabs may be provided at a 100

plurality of points, preferably near the four corners, with bolt holes, 6, extending through the same, the flats having similar, similarly-disposed bolt holes, 7, extending through the same. Suitable bolts, such as indicated at 8 in Fig. 4, may be inserted through the four groups of registering bolt holes in the slabs and flats so as to fasten the slabs and flats into what is in effect a single rigid block filled with cells containing the eggs or other articles. If desired, both the bolts for fastening the elements of the package together and the enclosing casing or box may be employed.

15 It will thus be seen that I have produced a simple and novel construction and arrangement made up of a plurality of duplicate slabs and a plurality of duplicate flats in which large quantities of eggs or other 20 fragile articles may be quickly and easily packaged, each being housed in an individual cell, and which will make it possible to ship such eggs or other articles long distances and under conditions which cause 25 packages to be carelessly handled, without danger of breaking the fragile contents; because the package is in effect a solid block honeycombed with cells each containing an individual article.

30 While I have illustrated and described with particularity only a single preferred form of my invention, I do not desire to be limited to the exact structural details thus illustrated and described; but intend to 35 cover all forms and arrangements which come within the terms employed in the definitions of my invention constituting the appended claims.

I claim:

40 1. In combination, a plurality of slabs superposed upon each other and having a plurality of registering holes extending through the same, comparatively thin flats lying between said slabs and interlocked 45 with the same.

12. In combination, a slab having a thickness at least equal to the length of articles to be packed, said slab having holes extending through the same, each hole being large 50 enough to receive one of said articles, and flats adapted to lie on the broad faces of said slab and close the ends of said holes.

3. In combination, a slab having a thickness at least equal to the length of articles 55 to be packed, said slab having holes extending through the same, each hole being large enough to receive one of said articles, and flats adapted to lie on the broad faces of said slab and close the ends of said holes, each of

said flats having flanges engaged in certain 60 of said holes.

4. In combination, a plurality of similar thick slabs arranged one upon another, comparatively thin flats lying against the bottom of the lowermost slab and upon the uppermost slab and serving as spacers between consecutive slabs, each slab having a thickness at least equal to the length of articles to be packed and being provided with holes extending through the same and each large enough to receive one of said articles.

5. In combination, a plurality of similar thick slabs arranged one upon another, comparatively thin flaps lying against the bottom of the lowermost slab and upon the uppermost slab and serving as spacers between consecutive slabs, each slab having a thickness at least equal to the length of articles to be packed and being provided with holes extending through the same and each large enough to receive one of said articles, each flat having annular ribs or flanges projecting therefrom and fitting into certain of the holes in the slab or slabs with which the flat engages.

6. In combination, a plurality of similar thick slabs arranged one upon another, comparatively thin flats lying against the bottom of the lowermost slab and upon the uppermost slab and serving as spacers between consecutive slabs, each slab having a thickness at least equal to the length of articles to be packed and being provided with holes extending through the same, and each large enough to receive one of said articles, there being registering bolt-receiving holes extending through said slabs and said flats, and bolts arranged in the said bolt-receiving holes.

7. In combination, a plurality of similar thick slabs arranged one upon another, comparatively thin flats lying against the bottom of the lowermost slab and upon the uppermost slab and serving as spacers between consecutive slabs, each slab having a thickness at least equal to the length of articles to be packed and being provided with holes extending through the same and each large enough to receive one of said articles, each flat having projections entered in certain of the aforesaid holes to interlock the stack of slabs and flats together, the slabs and flats having registering bolt holes, and bolts extending through said bolt holes.

In testimony whereof, I sign this specification.

LEOPOLD OXHANDLER.
